[57] CLAIM

The ornamental design for a projection television cabinet or similar article, as shown and described.

DESCRIPTION

FIG. 1 is a partial front, top and left side perspective view of a projection television cabinet or similar article showing my new design;

FIG. 2 is a top plan view thereof;

FIG. 3 is a right side elevational view thereof;

FIG. 4 is a front elevational view thereof, with the lens casing, which is unshaded for convenience of illustration, being identical to its appearance in FIGS. 1-3; and
FIG. 5 is a rear elevational view thereof.***Fig. 1***
